UNITED STATES PATENT OFFICE.

THOMAS GOODENOUGH, OF WOODSIDE, ASSIGNOR TO THE AKBAR MANUFACTURING COMPANY, OF NEW YORK, N. Y.

PNEUMATIC DOOR-CHECK.

SPECIFICATION forming part of Letters Patent No. 393,429, dated November 27, 1888.

Application filed May 4, 1888. Serial No. 272,774. (No model.)

To all whom it may concern:

Be it known that I, THOMAS GOODENOUGH, of Woodside, Queens county, New York, have invented a certain new and useful Improvement 5 in Door Checks, of which the following is a specification.

I will describe my improvement in detail and then point out the novel features in the claims.

10 In the accompanying drawings, Figure 1 is a face view of a door check embodying my improvement applied to a door, the door being closed. Fig. 2 is a plan or top view of the same the door being open. Fig. 3 is a face view 15 of the door-check, a portion of the outer shell or case being broken away to disclose the interior, and looking upwardly from Fig. 1. Fig. 4 is an enlarged view in section of a certain vent employed.

20 Similar letters of reference designate corresponding parts in all the figures.

A designates a case or shell. This case or shell may be cast in one piece. It comprises two cylindrical portions, a a' . Cap pieces a^2 , 25 having a screw-threaded connection with the ends of the case or shell, may be employed to close the outer ends of the cylinders. In the example of my improvement shown the cylindrical portion a is longer than the portion a' . Within 30 the cylindrical portion a is arranged a coil-spring, B, which abuts at one end against the cap-piece a^2 at the outer end of the portion a and at the other against a plate, a^3 . The plate a^3 has rigidly secured to it at about its center 35 one end of a rack, C. The rack C and plate a^3 constitute a plunger. The rack C is of sufficient length to extend into the cylindrical portion a' of the shell. Upon its end within the portion a' is secured a piston, D. This 40 piston may be provided with any suitable packing to secure an air-tight joint. The portion a' constitutes a pneumatic cylinder.

When a door having my check applied to it is opened, the spring B is compressed and the 45 piston D is withdrawn, air being admitted freely to cylindrical portion a' inward of the piston. These operations are accomplished as follows:

F designates a pinion mounted upon a shaft, 50 f , having suitable bearings in a portion of the case or shell A, intermediate of the cylin-

drical portions a a' . The pinion F gears with the rack C. One end of the shaft f extends beyond the case or shell A and has secured to it one end of a lever, G. This lever is provided 55 with a longitudinally-extending slot, g , having closed ends.

J designates a pin or projection extending into the slot g in the lever. This pin or projection forms part of a bracket, which bracket 60 is secured to the door by screws or otherwise. It is advantageous to form the bracket in two sections, j j' , adapted to slide one upon the other, but yet so engaged as not to be liable to lateral displacement. The sections j j' are provided 65 with longitudinal slots, through which extends a clamping-screw, g' , whereby the parts j j' may be secured in any position into which they may be adjusted in a well-known manner. This admits of accommodating the 70 device to doors having different depths of door-frame.

It will be readily seen that when the door is opened the lever G will move along on the pin or projection J, thus causing a rotation of the 75 shaft f , and consequently of the pinion F, whereby the rack C will be moved in a direction to compress the spring B. When the door is released, the spring operates to cause a reverse movement of the parts and a consequent 80 closing of the door. The check is, however, slow-closing.

As previously stated, when the door is being opened air is admitted freely to the pneumatic cylinder. The chief resistance therefore offered 85 to the opening of the door is that of the spring B. The resistance offered to the closing of the door is, on the contrary, that of an air-cushion formed in the pneumatic cylinder. This air-cushion is destroyed very slowly, so that the 90 door may close gently and without slamming. In effecting this operation I employ a vent of peculiar construction, (shown more clearly in Fig. 4,) in which H designates a valve. From the valve H extends a spindle, h , which acts as 95 a guide to the movement of the valve. The valve in this example of my improvement is arranged in a valve-chamber, h' , formed by a hollow metal piece, h^2 , which is open at its inner end, and is provided with a stop-pin, h^3 , 100 near its inner end to prevent the valve from passing out of the chamber. The metal piece

h^2 is screw-threaded externally, and engages a tapped hole, h^4 , in the cap a^2 , whereby it is retained in place. The outer portion of the metal piece h^2 is enlarged in the example of my improvement shown into the form of a bolt-head, h^5 . The valve seat h^5 for the valve H is within the bolt head. The spindle h plays loosely through an aperture, h^6 , extending about centrally through the bolt-head h^5 . Between the bolt-head h^5 and the cap a^2 is a washer, h^8 , which may be of leather. The screw-threaded portion of the metal piece h^2 engages somewhat loosely with the tapped hole h^4 . When the door is being opened and the piston D withdrawn, the valve H is drawn backwardly by the pressure of air from the outside, and air enters the pneumatic cylinder freely through the aperture h^6 in the bolt-head h^5 . When the door is being closed and the piston is being returned, the pressure of air from within immediately forces the valve H to its seat. An air-cushion is then formed between the piston D and the cap a^2 , which is only destroyed by the slow passage of air outwardly between the screw-threaded portion of the metal piece h^2 and the wall of the tapped hole h^4 , and between the washer h^8 and the cap a^2 . The rapidity with which the door will close may be regulated as desired by merely rotating the metal piece h^2 to increase or decrease the pressure which shall be exerted by the bolt-head h^5 upon the washer h^8 .

The case or shell A may be mounted upon a base-plate, J' , to which it may be secured by screws i , passing through holes in lugs i^2 on the case or shell.

The shaft f may be made to extend upon either side of the case or shell in order to accommodate right and left handed doors.

40 The check will usually be mounted on the door-casing and the pin or projection J on the door; but of course these positions might be reversed.

I do not mean to limit myself to the precise details of construction herein set forth, as it is obvious that a workman might alter the same and yet employ my invention. For instance, for the pinion and rack shown might be substituted other devices in operative engagement which would readily suggest themselves to the mind of a mechanic without departing from the spirit of my invention.

What I claim as my invention, and desire to secure by Letters Patent, is—

1. In a door check, the combination, with a pneumatic cylinder, of a spring arranged beyond the portion of the cylinder traveled by the piston of such cylinder, a connection between the piston rod and the spring, a lever for operating the piston and spring in operative engagement with the piston-rod intermediate of the spring and the piston, and a vent on the pneumatic cylinder, the whole being adapted to be arranged upon a door and door-easing, one of which is provided with a pin or projection having a sliding connection with the lever, substantially as specified.

2. In a door-check, the combination, with a case or shell comprising a pneumatic cylinder, of a piston, a rack connected to the piston, a spring opposing the movement of the piston in one direction and moving the piston in the other direction, a pinion engaging said rack, a lever for operating the pinion, and a vent on the pneumatic cylinder, the whole being adapted to be arranged on a door and door-easing, one of which is provided with a pin or projection having a connection with said lever, substantially as specified.

THOMAS GOODENOUGH.
